LOOSE-LEAF BINDER

Clarence D. Trussell, Poughkeepsie, N. Y., assignor to Trussell Manufacturing Company, Poughkeepsie, N. Y., a corporation of New York

Application November 16, 1938, Serial No. 240,655

2 Claims. (Cl. 129—24)

The invention disclosed herein relates to binders of the type in which the binder rings are in the form of cooperating prongs carried by spring tensioned toggle plates.

Special objects of the invention are to enable quick and easy closing of such binders and the securing of the binder in the position to which it is operated. Further, to provide such securing means in a form which may be readily released when desired to operate the binder in the reverse relation.

Other objects are to lighten the weight, simplify and reduce the cost and to promote smooth easy operation of the binder.

15 The foregoing and other desirable objects are attained in the present invention by the novel features of construction, combinations and relations of parts hereinafter described, illustrated in the accompanying drawing and covered in the 20 claims.

The drawing accompanying and forming part of the specification illustrates one practical commercial embodiment of the invention. The structure however may be modified and changed 25 as regards the present illustration all within the true intent of the invention, as broadly defined in the claims.

Fig. 1 is a broken and part sectional plan view of the ring metal.

30 Fig. 2 is an end view, illustrating the lower end in Fig. 1.

Fig. 3 is a cross-sectional view on substantially the plane of line 3—3 of Fig. 1.

Fig. 4 is a side view with part of the spring 35 cover plate broken away and in longitudinal section.

Fig. 5 is an enlarged broken sectional detail as on line 5—5, Fig. 2, showing the latch parts engaged, and Fig. 6 is a similar view illustrating the latch released.

40 The ring metal forming the subject of the present invention is of particularly light, simple and inexpensive design consisting in general of two sheet metal toggle plates or bars 7, 8, having mating ring forming prongs 9, 10, projecting from the opposite outer edges, said plates having their inner edges interlocked in rocking engagement at 11, and held in the spring toggle relationship by a spring cover plate 12, provided with 45 downturned confining flanges 13, 14.

The cover plate is notched in its opposite edges at 15, to provide free clearance for the ring forming prongs.

To insure smooth easy toggle action, the outer 50 edges of the toggle plates are notched at oppo-

site edges of the ring forming prongs as indicated at 16, in register with the slots 15, in the cover plate. This notching of the edges of the plates in addition to assuring free clearance for the prongs, segregates the intermediate edge portions 17, between the notches which then act as a series of longitudinally spaced separate independent bearings, rocking in the side channels behind the confining flanges of the cover plate.

To enable quick, easy and positive ring opening and ring closing movements, oppositely acting finger levers are provided at the opposite ends of the ring metal. One pair of opposed finger levers designated 18, project straight up from the toggle plates at one end of the binder, to 15 serve, when pinched together, to rock the plates in a ring closing direction and the other pair of finger levers 19, projecting from the plates in crossed relation at the opposite end of the binder, 20 serve when pinched together to rock the plates in a ring closing direction.

Some means are desirably provided for securing the rings in closed condition. The crossed portions of the closing levers afford a practical and convenient base for such a locking means.

In the illustration, the lock consists of a spring lug 20, struck out of one lever and having an abrupt edge at the outstruck end of the same for engagement with a correspondingly abrupt edge or shoulder 21 on the other lever. These 30 companion locking shoulders on the crossed portions of the levers, when interlocked are substantially parallel, directly above and on a radial line in respect to the hinge 11, between the plates substantially as indicated in Fig. 2. Also these co-operating locking shoulders are so disposed that they will engage only after the closing levers 18, 35 have been squeezed together, sufficiently to bring the ring forming prongs together in firm engagement. Engaged thus under tension, the 40 locking shoulders of the opening levers are held so and will not shake loose or accidentally release the toggle plates.

While the locking means described is positive and secure in its holding action, it may nevertheless be quickly and easily released by a simple 45 rotative or twisting pressure on the levers 19 in the direction of the arrows, Fig. 6, which will tend to spring one away from the other, thus to relatively shift the companion shoulders into 50 fully separated condition, where the levers may then be freely actuated to effect opening of the rings. The levers therefore preferably are made of spring material or have sufficient spring action to permit yielding of one in respect to the other 55

- as the outwardly projecting lug on one slides over the face of the other into engagement in back of the locking shoulder and to permit the necessary twisting action for effecting release of the companion locking elements. For such reasons, the opening levers may be made of harder spring material, and be attached to the ends of the toggle plates by spot welding or the like, in the manner indicated at 22, in Fig. 4.
- 10 What is claimed is:
1. A loose-leaf binder, comprising toggle plates engaging on a common toggle center, said plates being mounted for rocking movement and carrying cooperating ring forming elements, finger levers projecting each from a plate at one side of the toggle center to the opposite side of said toggle center in crossed overlapping relation and having finger grips at the ends of the same spaced in the closed position of the ring forming elements so that the plates may be rocked to the open ring position by pinching said spaced finger grip ends of the crossed finger levers toward each other, the crossing portions of said finger levers having abrupt locking shoulders located intermediate the finger grip ends and the points of attachment of said levers to the plates and disposed to register in the position of said levers in the ring closed position of the toggle plates, one of said locking shoulders being offset from the general plane of the lever carrying the same into the plane of the locking shoulder on the other lever to thereby stand in opposition thereto in the closed condition of the rings and said finger levers being sufficiently yieldable to enable clearance of one locking shoulder from the other being effected by relative twisting movement applied to the finger grip ends of the levers as a preliminary to the pinching action required to impart ring opening movement to the toggle plates.
  2. A loose-leaf binder, comprising toggle plates engaging on a common toggle center, said plates being mounted for rocking movement and carrying cooperating ring forming elements, finger levers projecting each from a plate at one side of the toggle center to the opposite side of said toggle center in crossed overlapping relation and having finger grips at the ends of the same spaced in the closed position of the ring forming elements so that the plates may be rocked to the open ring position by pinching said spaced finger grip ends of the crossed finger levers toward each other, the crossing portions of said finger levers having abrupt locking shoulders located intermediate the finger grip ends and the points of attachment of said levers to the plates and disposed to register in the position of said levers in the ring closed position of the toggle plates, one of said locking shoulders being offset from the general plane of the lever carrying the same into the plane of the locking shoulder on the other lever to thereby stand in opposition thereto in the closed condition of the rings and said finger levers being sufficiently yieldable to enable clearance of one locking shoulder from the other being effected by relative twisting movement applied to the finger grip ends of the levers as a preliminary to the pinching action required to 10
